DESIGN FOR A BILLFOLD

John P. Reis, West Bend, Wis., assignor to Amity Leather Products Co., West Bend, Wis., a corporation of Wisconsin

Application October 18, 1946, Serial No. 134,028

Term of patent 3½ years

(Cl. D87—3)

To all whom it may concern:

Be it known, that I, John P. Reis, a citizen of the United States, residing at West Bend, in the county of Washington and State of Wisconsin, have invented a new, original, and ornamental Design for a Billfold, of which the following is a specification, reference being had to the accompanying drawing, forming a part thereof, and in which:

The back of the billfold is substantially plain. I claim:

The ornamental design for a billfold, substantially as shown and described.

JOHN P. REIS.
